UNITED STATES PATENT OFFICE.

WILLIAM E. SMITH, OF MILLTOWN, NEW JERSEY, ASSIGNEE TO KILBOURN MANUFACTURING CORPORATION, OF NEW BRUNSWICK, NEW JERSEY, A CORPORATION OF NEW JERSEY.

TOPPING-MACHINE.

1,116,637.

Specification of Letters Patent. Patented Nov. 10, 1914.

Application filed June 30, 1914. Serial No. 848,125.

To all whom it may concern:

Be it known that I, WILLIAM E. SMITH, a citizen of the United States, residing at Milltown, in the county of Middlesex and 5 State of New Jersey, have invented new and useful Improvements in Topping-Machines; and I do hereby declare the following to be a full, clear, and exact description of the invention, such as will enable others 10 skilled in the art to which it appertains to make and use the same.

My invention consists in the novel features hereinafter described, reference being had to the accompanying drawings which 15 show several embodiments of my invention which I have selected for the purpose of illustrating the same, and my said invention is fully disclosed in the following description and claims.

20 My invention relates to topping machines or machines for transferring ribbed tops of stockings, and the embodiments of my invention which I have selected for the purpose of illustrating the same, are designed 25 to be used in connection with the type of topping machine shown in Letters Patent of the United States #1,035,601, granted to E. E. Kilbourn, myself, and I. W. Kilbourn, under date of August 13, 1912, although I 30 do not limit the use of my invention to this particular machine.

In knitting seamless half-hose, the tops of the stockings are knitted on a rib machine provided with cylinder and dial needles in 35 the form of a continuous tubular web, sections of which are employed for the tops of half-hose, and the transfer machines to which this invention relates, are adapted to feed the tubular ribbed material in the form 40 of a continuous tubular web to a predetermined position in which the stitches of the course to be transferred are brought into alinement with transfer levers and by the operation of the machine, the transfer levers 45 are caused to pass through stitches of the course to be transferred, and to distend the web into position to bring all of the stitches of the course to be transferred into alinement with the quills of the transfer ring, (or the needles of a circular knitting machine) and apply the same thereto, the section of the ribbed fabric sufficient for a single ribbed top being then cut from the strip of fabric, and the operation repeated. 50 The ribbed fabric is preferably knit with a

selvage welt adjacent to one end of each section thereof and a loose or slack course of stitches adjacent to the other end to facilitate the transfer operation and in order to enable the transferring or topping machine 60 to correctly position the ribbed fabric with respect to the transfer levers, the ribbed fabric is provided between the loose or slack course of stitches and the point adjacent thereto where the fabric is to be severed, 65 with an extra positioning welt, as shown in United States Letters Patent to E. E. Kilbourn #953,669, dated March 29th, 1910, and in my former Patent #1,009,450, dated November 21, 1911, the said extra welt or 70 positioning welt being provided in the ribbed fabric for the express purpose of being engaged by the ends of the registering bits of the transferring machine which slide in the grooves between the wales on the exterior of the ribbed fabric while said fabric is partially distended by a central mandrel, and said positioning welt and the adjacent portions of the fabric between the line of severance and the slack course of stitches or 75 transfer course is unraveled after the ribbed top has been applied to the needles of the circular knitting machine, before knitting the stocking, as is fully set forth in the various patents before referred to. The transferring or topping machine is provided with a circular series of these registering bits surrounding the mandrel and in the operation of the machine, the said bits are moved into engagement with the positioning welt and 80 thereafter move the ribbed fabric lengthwise of the mandrel so as to bring the adjacent transfer course or slack course into alinement with the points of the transfer levers and hold the fabric in that position 85 until the transfer levers have penetrated the stitches of the slack course or transfer course.

In the machine shown and described in the Patent #1,035,601, before referred to, 100 the registering bits are pivotally mounted at their rear ends and are yieldingly held in engagement with the fabric and pressed into the grooves between the wales thereof by an annular elastic connection preferably 105 in the form of an endless spiral spring engaging grooves or recesses in the forward ends of the bits. It sometimes happens that these bits in passing over a thicker portion of the fabric or over a slight lump or pro- 110

tuberance therein are forced outwardly and these outward movements of the bits have a tendency to raise the extreme points of the bits out of the bottom of the grooves between adjacent wales and might in some instances force them out of the groove or out of proper engagement with the positioning welt. One of the objects of my present invention therefore, is to provide an improved form of registering bit in which the runner, or portion thereof which engages the groove in the fabric, is pivotally connected to the body of the bit and extends forward and rearwardly of the pivotal connection so that the runner portion of the bit is enabled to adjust itself to any variations in thickness of material or lumps in the fabric and if one end of the runner is raised in passing over such thickened portions, or over a welt, the other end will be more firmly pressed into the groove. I also preferably provide the central portion of the bottom face of the runner portion of the bit with a recess or cutaway portion beneath the pivotal connection to accommodate such thickened portion as the runner moves over the same and prevent the runner being raised bodily out of the groove by the passage of such welt, thickened portion, or lump beneath the pivotal connection of the runner with the bit body. It therefore follows that at all times at least one end of the runner must be firmly pressed into the corresponding groove of the fabric and in case a runner passes over a lump or thickened portion which tends to lift one end of the same, as it passes beneath the recessed portion of the runner, the elevated end will be permitted to descend into the groove before the other end is elevated in passing over the lump or thickened portion.

In the operation of the machine shown and described in Patent #1,035,601, before referred to, the number of transfer levers is equal to one half the number of stitches in the transfer course or slack course to be transferred and in the machine shown in that patent, when the bits have positioned the transfer course, they lie over the alternate stitches of the course to be transferred, to wit, those at the bottom of the several grooves between the wales, which I term the dial stitches to distinguish them from the cylinder stitches of the fabric, which appear at the top of the wales and which are exposed between the several bits and are taken by the transfer levers. In the machine described in said patent, therefore, every alternate stitch is taken by the transfer levers and the intermediate stitches are held in position to properly engage the appropriate quills of the transfer ring by the tension of the stitches so engaged by the transfer levers.

In some instances, as for example, in the case of very coarse work, it is desirable in

order to secure absolutely accurate transferring, to use a transfer lever for each and every stitch of the slack course or course to be transferred, and this presents difficulties, for the reason that alternate or dial stitches lie beneath the bits of the transferring machine and the bits must be maintained in contact with the positioning welt until after the engagement of the transfer levers with the stitches of the slack course in order to insure the proper operation of the transfer levers. In my improved bit which forms the subject matter of this invention, I obviate the difficulty above noted and provide for the proper engagement of the additional transfer levers with the dial stitches below the bits by so constructing the runner portions of my improved bits that the alternate transfer levers may pass through recessed portions thereof and engage the stitches beneath the same, while the bits are pressed up against the extra welt to position the slack course of stitches. This result may be accomplished in several ways and I prefer to employ with the body of each registering bit, two runners arranged side by side and pivotally connected centrally with the body of the bit, leaving a sufficient space between the runners for the passage of one of the transfer levers to enable it to engage the dial stitch beneath said duplex runner, or in some instances, I may form the runner in one piece and provide it with a recess at one end on one side thereof for the purpose of accommodating the transfer lever and permit it to enter the dial stitch below the runner.

In the accompanying drawings, Figure 1 represents portions of a transferring or topping machine showing my invention applied thereto. Fig. 2 is an enlarged detail perspective view showing a portion of the ribbed fabric greatly enlarged, a portion of the supporting mandrel of the topping machine, and one of my improved registering bits in position with respect to the extra welt or positioning welt of the fabric and the slack or loose course thereof. Fig. 3 is a top plan view of one of my improved bits detached. Fig. 4 is a similar view showing a slight modification. Fig. 5 is a vertical section on line 5-5 of Fig. 4. Fig. 6 is a side elevation of another modification of my improved bit, and Fig. 7 is a top plan view of the bit shown in Fig. 6.

In Fig. 1, I have shown so much of a topping machine or transferring machine as is necessary for an understanding of my present invention. In this figure, 1 represents the transfer ring which is detachably supported in the machine upon a suitable supporting frame 2; 3 is the supporting mandrel of the machine provided with an annular series of supporting fingers 4, and circular brush portion 5, for supporting the

tubular fabric while permitting the engagement of the transfer levers and the severing of the fabric, and 6, 6 represent two of the circular series of transfer levers, it being understood that they may be equal in number to the total number of stitches in the slack course or transfer course, as hereinabove described, or may be of a number equal to one half the total number of stitches in said course, as preferred. 10 represents the main body of one of my improved bits which is pivotally connected at 11 to the bit supporting frame of the transfer machine, not herein shown. The said body of the bit is provided adjacent to its outer end with a recess 12 to receive the yielding band or spring 13 for pressing the bits into the grooves between the wales of the fabric. 14, 14 represent a pair of runners pivotally connected to the body 10 of the bits 15, and in the form of the invention shown in Figs. 1, 2, and 3, lying at opposite sides of the bit body 10, the forward ends of the runners being inclined upwardly and rearwardly as 25 at 16, to provide for the effective engagement of the runners at their forward bottom edges with the positioning welt of said fabric, and each of said runners being provided with a recess in its lower edge as at 17, below the point of pivoting 15. 20 represents the ribbed fabric provided with the wales 21 and alternate grooves 22; 23 representing the selvage welt of one section of the fabric; 24 representing the slack course or transfer course of stitches, and dotted line 25—25 representing the line of severance between two adjacent sections of the fabric or ribbed tops. 26 represents the extra welt or positioning welt, which as will be apparent, is located between the slack course of stitches 24 and the line 25—25 of severance, between the sections, and is engaged by the forward ends of the runners to move the fabric into such position that the transfer levers will 45 engage the stitches of the slack course or transfer course. It will be noted that the stitches of the slack course at the bottom of the grooves 22, which are indicated at 24^a, will lie beneath the runner portion of the bit, but in the form of runners shown in Figs. 1, 2, and 3, a space is provided between the runners 14—14 so that a transfer lever may pass between the same and engage the stitch 24^a at the bottom of the groove. In 50 some instances I may employ a single runner 14^a pivotally connected to the body 10^a, as indicated in Figs. 4 to 7 inclusive and in such case, the forward end of the body 10^a may be bifurcated, as shown at 10^b, to embrace the runner 14^a to which said bifurcated portions are pivotally connected by the pivot pin 15^a, the said runner being provided with a recess 17 in its lower edge, see particularly Fig. 5. If it is desired to use 55 this form of single runner, in a machine

provided with a transfer lever, for every stitch, the forward end portion of the runner may be provided with a recess 27 at one side thereof, as shown in Fig. 4, to accommodate the transfer lever for the dial stitch beneath the runner, or the said runner may be provided with a recess 28, as shown in Figs. 6 and 7, in the extreme end thereof, for the same purpose.

In the forms of bit herein shown and described, it will be apparent that the pivoted runner is free to rise and fall at each end independently, and thus accommodate itself to variations in the thickness of the fabric or projections or protuberance, such as knots or lumps in the yarn which may occur in the grooves between adjacent wales, as they traverse the same. It will also be seen that if the front end of a runner is raised to pass over such a lump or thickened portion, the rear end will be pressed even more firmly into the groove and as the lump or thicker portion passes under the recessed portions 17, beneath the point of pivoting, the forward end of the runner will descend and be pressed firmly against the bottom of the groove before the rear end can be raised from the bottom of the lump or projection, so that at all times one or both ends of the runner will be firmly pressed against the bottom of the groove and the bits are therefore prevented from at any time becoming disengaged from the grooves of the fabric or from being moved out of position to properly engage the positioning welt 26 of the 100 fabric.

It will be noted that the rear extremities of the runner are preferably curved upwardly and rearwardly, or beveled, to enable the runners to ride easily over the fabric when the fabric is drawn forward with respect to the bits, or the bits are moved rearwardly with respect to the fabric. It will also be understood that when the welts of the fabric, either the selvage welt or welts, or the special positioning welts, pass under the pivotally mounted bits, the rear end of each runner will be first elevated, which will depress the forward end of the runner more firmly in the bottom of the groove, and as the welt reaches the recess in the bottom of the runner beneath the pivotal connection thereof with the bit body, the rear end of the runner will descend into the groove of the fabric before the forward end is elevated, as the welt passes beneath the same, so that one or both ends of the pivoted runner is or are at all times firmly pressed into a groove of the fabric and the twisting of the fabric as it is fed through the 115 machine is positively prevented.

What I claim and desire to secure by Letters Patent is:—

1. In a machine for running on seamless knitted web, the combination with a sup- 130

- porting mandrel, and a series of transfer levers, of a plurality of registering bits, said bits being provided with runners pivotally connected thereto, for engaging the grooves between adjacent wales of the knitted fabric, whereby said runners can adapt themselves to irregularities in the surface of the fabric traversed thereby.
2. In a machine for running on seamless knitted web, the combination with a supporting mandrel, and a series of transfer levers, of a plurality of registering bits, said bits being provided with longitudinally disposed runners pivotally connected between their forward and rear ends to the bits, whereby said runners engage the grooves between adjacent wales of the fabric and adjust themselves to irregularities in the surface traversed thereby.
3. In a machine for running on seamless knitted web, the combination with a supporting mandrel, and a series of transfer levers, of a plurality of registering bits, said bits being provided with runners pivotally connected thereto, said runners having their under surfaces recessed beneath the point of pivoting, whereby one or both end portions of the runners are at all times maintained in the grooves of the fabric.
4. In a machine for running on seamless knitted web, the combination with a supporting mandrel, and a series of transfer levers, of a plurality of registering bits, each of said bits comprising a pivoted body portion having its outer end provided with a runner pivotally connected therewith, and having portions extending forward and rearward of the point of pivoting, each of said bits having its forward end provided with means for permitting the passage of a transfer lever to and through the stitch of the transfer course beneath the same.
5. In a machine for running on seamless knitted web, the combination with a supporting mandrel, and a series of transfer levers, of a plurality of registering bits, each of said bits being provided with a runner pivotally connected therewith, said runners being provided with recessed portions to permit the passage of a transfer lever therethrough to engage a stitch of the course to be transferred, lying at the bottom of a groove of the fabric beneath said runner.
6. In a machine for running on seamless knitted web, the combination with a supporting mandrel, and a series of transfer levers, of a plurality of registering bits, each of said bits being provided with a pair of runners pivotally connected thereto, and having their forward ends separated a sufficient distance to permit of the passage of a transfer lever between said runners to engage a stitch of the course to be transferred, lying below said runners.

In testimony whereof I affix my signature, in the presence of two witnesses:

WILLIAM E. SMITH.
